UNITED STATES PATENT OFFICE

RICHARD A. WAGSTAFF, OF SALT LAKE CITY, UTAH, ASSIGNOR TO AMERICAN SMCLETTING AND REFINING COMPANY, OF NEW YORK, N. Y., A CORPORATION OF NEW JERSEY

SMELTING FURNACE AND METHOD OF SMELTING

Application filed June 27, 1925. Serial No. 39,894.

This invention relates especially to smelting processes and furnaces of the reverberatory type adapted for the treatment of copper, zinc or other ores, etc. and the invention 5 relates especially to the type of smelting furnace in which the melt flows from the firing or smelting chamber away from the stack and preferably in the opposite direction to the movement of the flue gases so that the melt 10 flows into a separate or distinct settling chamber where it may be heated or otherwise treated to the desired extent and where the settling and separation of the matte and slag can take place under ideal conditions and in 15 a very advantageous way. It is also advantageous to provide in the smelting chamber a water jacketed or other suitable bridge wall which may more or less surround the charge except toward the burners or firing means 20 and the charge may be advantageously supported on a shelf of refractory lump material such as chrome ore or the like which materially minimizes furnace replacements.

In the accompanying drawing showing in 25 a somewhat diagrammatic way an illustrative embodiment of this invention,

Fig. 1 is a longitudinal section; and

Fig. 2 is a top view of the illustrative furnace.

The firing or smelting chamber 1 of the furnace may be formed with a roof preferably though not necessarily of the arched type which for high smelting heats is preferably constructed of silica brick, and this roof 35 may be provided with a series of feed hoppers such as 18 and co-operating feed passages 20 more or less extending through the water cooled or other feed plate 19 supported so as to extend transversely across the 40 smelting chamber. In this way the charge 10 may be continuously or intermittently fed into the smelting chamber preferably within the more or less enclosing bridge walls 14, 30 which may be of the ordinary water 45 jacket construction; and it is desirable in many cases to provide adjacent the bridge wall a refractory backing 12 formed of silica or chrome brick which are desirable for this purpose, so as to form a more or less inclined 50 support preventing undesirable accumula-

tion of the charge. The charge may be advantageously supported on a shelf such as 9 of refractory lump material such as chrome ore or the like which may of course be fired into the furnace in connection with more or less fluxed material. This shelf as indicated 55 may extend between the masonry foundation 11 of the bridge wall 14 and the foot wall 7 toward the tapping end of the furnace, the shelf being of course supported on the furnace bed 38 of any suitable material.

This smelting chamber may be heated in any suitable way as by a series of oil or powdered coal burners 22 which may approach through firing openings 29 extending more 60 or less across the suspended bridge wall of the furnace, and in this way the heat may be directed toward the inclined smelting face of the charge which may be heated to the desired degree and subjected to the desired 65 flame treatment at the same time. The hot gases passing over the charge move in the direction of the arrows 36 into the stack chamber or flue 17 so that the flue dust 15 is more or less deposited against the bridge 70 wall 14 for instance. This stack flue may have one or more waste heat boilers 32 of any desired construction on one or both sides of the longitudinal partitions such as 31, 39 shown diagrammatically in Fig. 2.

The separate settling chamber 2 of any desired shape and construction is arranged at the tapping side of the furnace so as to be if desired on the opposite side of the smelting charge from the flue or stack and to preferably have a low arch or small area connection with the smelting chamber; and a suitable hearth 4 may be provided beneath this settling chamber which may as indicated in Fig. 2 have a somewhat elongated shape so 80 as to extend to the tapping end or wall 40 of the furnace which may be formed with a slag hole 24 and matte tapping hole 25 having the usual tapping plugs 26. One or more auxiliary burner or inspection apertures may 85 be formed in this settling chamber and adjacent parts of the furnace such, for example, one or more burner apertures 23 in the tapping wall 40 and smelting burner apertures 90 35 in the cross wall 41 of the furnace, also

inspection or treating apertures such as 28, 21 and 37 may be formed in the furnace top.

In smelting copper or zinc ores in this type of furnace the uniform heating and treating action of the flame on the charge in the smelting chamber is very desirable in making possible the more exact smelting treatment of the charge; and it is particularly desirable to have the resulting melt withdrawn into the settling chamber and away from the contamination of the flue dust and fresh charge so as to promote settling of the matte below the line 27; and in this way considerable reduction in the copper loss in the slag is possible with this furnace and smelting method. This is of course effected most advantageously when the melt is withdrawn from the smelting chamber in the opposite direction from the movement of the burner flames and flue gases so as to give in a way a counter-current operation of the furnace; and this makes possible savings in the fuel consumption as well as giving a large recovery of waste heat in the boilers which may be used in the stack flue as indicated. By using a shelf of lump chrome ore construction to support the charge destructive action on this part of the furnace lining is considerably minimized and of course the melt by being withdrawn from the intensely hot firing zone or chamber of the furnace can be maintained at any desired heat, and in many cases where special heat treatment is unnecessary relatively lower heats may be used in this part of the furnace so as to correspondingly reduce corrosive action by the slag and resulting maintenance charges.

This invention has been described in connection with an illustrative form of furnace and smelting process, to the details of which disclosure the invention is of course not to be limited, since what is claimed as new and what is desired to be secured by Letters Patent is set forth in the appended claims:

45. 1. A smelting furnace comprising a stack flue and a communicating smelting chamber having a refractory charge shelf formed of fired lumps of chrome ore, a transverse series of burners directed into said smelting chamber toward said stack flue, a cooled bridge wall adjacent said shelf and having a refractory backing to support the charge being smelted, a transverse series of feeding means adapted to continuously feed said charge to said shelf and a relatively narrow low arch settling chamber communicating with said smelting chamber and on the opposite side thereof from said stack flue to withdraw the melt from the smelting charge for settling with minimum contamination by the charge and flue dust.

46. 2. A smelting furnace comprising a stack flue and a communicating smelting chamber having a refractory charge shelf, a transverse series of burners directed into said smelting

chamber toward said stack flue, a cooled bridge wall adjacent said shelf to support the charge being smelted, feeding means adapted to feed said charge to said shelf and a relatively low arch settling chamber communicating with said smelting chamber and away from said stack flue to withdraw the melt from the smelting charge for settling with minimum contamination by the charge and flue dust.

3. A reverberatory smelting furnace comprising a stack flue and communicating smelting chamber having an arch roof and a charge shelf formed of fired lumps of chrome ore, a transverse series of burners directed into said smelting chamber toward said stack flue, a water cooled bridge wall extending across the flue side of said shelf and having a refractory backing to support the charge being smelted, a transverse series of feed hoppers and channels adapted to continuously feed said charge and a settling chamber communicating with said smelting chamber and on the opposite side thereof from said stack flue to withdraw the melt from the smelting charge for settling with minimum contamination by the charge and flue dust.

4. A reverberatory smelting furnace comprising a stack flue and communicating smelting chamber having a charge shelf formed of fired lumps of chrome ore, a transverse series of burners directed into said smelting chamber toward said stack flue, a bridge wall extending across the flue side of said shelf to support the charge being smelted, a transverse series of feed hoppers and channels adapted to feed said charge and a settling chamber communicating with said smelting chamber and on the opposite side thereof from said stack flue to withdraw the melt from the smelting charge for settling with minimum contamination by the charge and flue dust.

5. A smelting furnace comprising a stack flue and a communicating smelting chamber having a refractory, chrome charge shelf and a bridge wall adjacent one end of said shelf, a series of burners directed toward said shelf and bridge wall, feeding means to feed the charge to said shelf adjacent said bridge wall and a settling chamber communicating with said smelting chamber and located out of the path of the flue gases from said burners to promote settling of the melt and minimize heat losses.

In testimony whereof I have hereunto set my hand.

RICHARD A. WAGSTAFF.
